UNITED STATES PATENT OFFICE

JOHN L. HULBERT, OF POUGHKEEPSIE, NEW YORK, ASSIGNOR TO THE DE LAVAL SEPARATOR COMPANY, OF NEW YORK, N. Y., A CORPORATION OF NEW JERSEY

CUTTER FOR LINERS OF MILKING-MACHINE TEAT CUPS

Application filed June 27, 1928. Serial No. 288,560.

The teat cups of some milking machines comprise a flexible and elastic (rubber) tube, called a "liner," which is stretched longitudinally within a metal shell and is held therein by engaging the ends of the liner with opposite ends of the shell or with members in fixed relation with the shell. These liners elongate with use and require to be cut to a shorter length. It is important that the liner should be trimmed to a predetermined length. The object of my invention is to provide means for trimming liners and to facilitate the trimming of the liners to a predetermined length. The invention comprises a cutting or trimming device by means of which the liner may be so trimmed that its length will be uniform along all longitudinal lines and which will be cheap to construct and easy to operate.

In the accompanying drawings, which show several of many different specific embodiments of my invention—

Fig. 1 is a side elevation of the mandrel with a cutter guide and holder mounted thereon.

Fig. 2 is an end view of the same.

Fig. 3 is a perspective view of the guide and holder of Figs. 1 and 2.

Fig. 4 is a perspective view of a modified construction of knife guide and holder.

Fig. 5 is a perspective view of another modified construction of knife guide and holder.

Referring first to the construction shown in Figs. 1, 2 and 3:

The base of the device is a mandrel *a* having end sections of different diameters and an intermediate tapered section.

The knife guiding and supporting device comprises wings *b*, *b*, adapted to fit on opposite sides of the enlarged end portion of the mandrel, a stop *c* adapted to abut against the end of the enlarged portion of the mandrel, a neck *d* extending forward of the side wings, and a knife-supporting plate *e* depending from the front end of the neck *d*. A knife *x* is held against the plate *e* by means of fingers *f*, *f*, behind which the knife has been forced and is maintained in proper position by bottom lugs *g*, *g*, and top lugs *h*, *h*. The

lugs and fingers may be integral with plate *e*. The bottom edge of plate *e*, between lugs *g*, *g*, may be concave to allow the knife edge to project below the plate. The neck *d* and the top edge of plate *e* may be cut away to facilitate the insertion and withdrawal of the knife.

In operation, the tubular liner is pushed over the smaller end portion of the mandrel until its trailing end aligns with a ring *i* cut in, or otherwise formed on, the mandrel. The advanced end will then have been forced over the tapered portion and onto the larger end portion of the mandrel.

The knife guide and holder is then presented to the larger end portion of the mandrel at an angle, as shown in broken lines, Fig. 1, with the stop *c* against the end of the mandrel and is then swung about an axis at right angles to that of the mandrel away from said broken line position until the guide wings *b*, *b*, pass at the mandrel's sides, as shown in the full line position, Fig. 1, and the knife contacts with the liner. While the knife is maintained pressed against the liner, the mandrel and the liner sleeved thereon are rotated, producing a smooth, true cut, and shortening the liner to the correct length.

In Fig. 4, the neck *k* of the guiding and supporting device is extended upward and thence downward to form the opposing plates *m* and *n* of a clamp for receiving and holding the knife blade.

In Fig. 5 the construction is the same as in Fig. 4 except that the front member *o* of the clamp is provided with laterally and downwardly extending ears *p* which extend beyond the corners of the knife *x* and eliminate danger of the user cutting his fingers.

Having now fully described my invention, what I claim and desire to protect by Letters Patent is:

1. In a rubber tube trimmer, the combination with a mandrel over which the tube is adapted to be stretched, of a knife-supporting member, a stop adapted to be pressed against one end of the mandrel, and a body connecting the stop and knife-supporting member and adapted to partly surround the mandrel, the knife being thereby held in a predetermined

position relative to the mandrel while the mandrel is relatively rotated within said body.

2. In a rubber tube trimmer, the combination with a mandrel over which the tube is adapted to be stretched, of a knife holder and guide comprising a knife clamp, a stop adapted to engage one end of the mandrel, and two wings adapted to fit on opposite sides of the mandrel and hold the knife in a predetermined position while the mandrel is rotated relative to the knife holder and guide.

3. In a rubber tube trimmer, the combination with a mandrel having ends of different diameters and a tapered portion between its ends and provided with an arcuate tube-positioning mark, of a knife holder and guide comprising a guide swingable into and out of engagement with the mandrel and within which the mandrel is rotatable when the guide is engaged therewith, a stop carried at one end of the guide and adapted to engage the larger diameter end of the mandrel and properly position the knife holder and guide longitudinally, and a knife holder carried at the other end of the body and adapted to so position the knife when the guide is in operative relation with the holder that the knife may be in cutting relation to the tube while the mandrel is rotated.

4. In a rubber tube trimmer, the combination with a mandrel over which the tube is adapted to be stretched, of a body adapted to be supported on the mandrel so as to extend longitudinally, and at an angle to the axis, of the mandrel and to be then swung down to bring the body into guiding relation with the mandrel so as to allow of the rotation of the mandrel therein, a knife-carrying member on the swingable end of the mandrel, and a knife carried by said member and adapted, when the body, by said swinging movement, is brought into guiding relation with the mandrel, to be brought toward cutting relation with the tube stretched on the mandrel.

5. In a rubber tube trimmer, the combination with a mandrel over which the tube is adapted to be stretched, of a channelled body and a knife carried thereby, said body and knife being movable respectively into guiding relation with the mandrel to allow of the rotation of the mandrel therein and into cutting relation with the tube stretched thereon.

6. In a rubber tube trimmer, the combination with a mandrel having opposite end portions of different diameters, the end portion of smaller diameter having an arcuate tube-positioning mark, the tube to be trimmed being adapted to be slipped on to and along the end of the mandrel of smaller diameter and engage the end portion of larger diameter, of a knife, and a knife-supporting member supportable on the larger diameter portion of the mandrel and movable into and out of position to place the knife in cutting relation with the

tube in the rotation of the mandrel relative to said member.

In testimony of which invention, I have hereunto set my hand at Poughkeepsie, New York, on this eighteenth day of June, 1928.

JOHN L. HULBERT.
